GEORGE LOTHAIN GREVES, OF BERKELEY, CALIFORNIA.

FREQUENCY-SELECTING RECEIVING-CIRCUIT.

1,366,830.

Specification of Letters Patent. Patented Jan. 25, 1921.

Application filed December 19, 1917. Serial No. 207,862.

To all whom it may concern:

Be it known that I, FREDERICK E. PERNOT, a citizen of the United States, and a resident of Berkeley, in the county of Alameda and 5 State of California, have invented new and useful Improvements in Frequency-Selecting Receiving-Circuits, of which the following is a specification.

My invention relates to improvements in 10 receiving circuits, and it consists in the combinations, constructions and arrangements herein described and claimed.

An object of my invention is to provide a receiving circuit tuned to receive one or more 15 predetermined tone frequencies to the substantial exclusion of all other frequencies, thereby preventing interference.

A further object of my invention is to provide for the simultaneous reception at a 20 single station of several tone frequencies from one or more sources.

Other objects and advantages will appear in the following specification and the novel features of the invention will be particularly pointed out in the appended claims.

My invention is illustrated in the accompanying drawing, forming a part of this application, in which

Figure 1 is a diagrammatic view showing 30 the connections for a receiving circuit for a single tone frequency and

Fig. 2 is a diagram of a circuit arranged to enable the receiving of a plurality of different tone frequencies, each independently 35 of the others.

The receiving circuit which forms the subject of this invention has certain portions which are in ordinary use and these portions will be described in order that the combination of the old elements and the new 40 which form the new combination, will be readily understood.

Referring then to Figs. 1 and 2 I have shown therein an aerial A which is connected with one of the windings D of an air-core transformer, the opposite end being grounded at G. The secondary winding E of the transformer is connected with one terminal of an audion F, the opposite terminal 45 of the coil being connected to the audion as shown in the drawing. Condensers H and K are used in the circuit, the condenser H being interposed between the end of the coil E and audion and the condenser K be-

ing bridged across the terminals of the winding E. A local circuit containing a battery B* heats the filament of the audion. A battery B is connected on one side with the audion F as shown, the plate of the audion being connected with a wire V. The receiving circuit as thus far described is ordinary. It has been used as a type of circuit which may be employed in connection with my improved receiving system.

The audion instead of being connected directly to the telephone receiver as in ordinary practice, is connected to an auxiliary circuit, which circuit serves to separate the different group frequencies delivered to it by the audion. Each auxiliary circuit as 60 shown in single application in Figure 1, includes an inductance coil L which is connected at one end to the battery B, the other end of the coil being connected with the wire V by means of a shiftable contact l. A variable condenser C is bridged across the terminals of the coil L. A telephone receiver R has one terminal connected with one end of the coil the other terminal being connected to an adjustable contact r. 65

The operation of the circuit shown in Fig. 1 is as follows: The impulses are received by the aerial in the usual manner and are transmitted to the audion. The current from the audion pulsates at the tone frequency of 70 the sending set and serves to excite the circuit L, C at this frequency. The circuit L, C may be adjusted either by varying the capacity of the condenser C or by shifting the contacts l or r. 75

The operation of the circuit shown in Fig. 1 is as follows: The impulses are received by the aerial in the usual manner and are transmitted to the audion. The current from the audion pulsates at the tone frequency of 80 the sending set and serves to excite the circuit L, C at this frequency. The circuit L, C may be adjusted either by varying the capacity of the condenser C or by shifting the contacts l or r. 85

In Fig. 2 I have shown an arrangement by which more than one operator may receive at the same time. This is accomplished by providing a plurality of circuits similar to the circuit L, C, of Fig. 1, these 90 circuits being shown at L₃, C₃ and at L₄, C₄, the former having the receiver R₃, and the latter having the receiver R₄. Each auxiliary receiver circuit is sensitive to one group frequency only, so that a single station 95 may receive simultaneously a plurality of group frequencies.

Take this example: a succession of electrical impulses emanating from one station may be at a certain radio frequency such 100 as one million cycles per second and at a certain group frequency, such as five hundred cycles per second. Another station

may send out impulses at the same radio frequency but at a group frequency of eight hundred cycles per second.

When these impulses reach the antenna

- 5 A of the set in Fig. 2, they will of course be unintelligible until they pass the audion F. It is now that the auxiliary circuits L_3 and L_4 perform their separating actions. Each circuit being tuned to the group frequencies of five hundred and eight hundred cycles per second respectively, make only those impulses of these particular group frequencies audible in the respective telephones R_3 and R_4 .
- 10 15 While I have shown the receiving circuit connected with an audion it is obvious that any suitable equivalent such as a crystal or other detector, might be used without departing from the spirit of the invention.
- 20 25 I also wish to call attention to the fact that the circuits as shown up to the auxiliary circuits, *i. e.* L , C , etc., are given only as examples, and that various changes might be made in said circuits without at all affecting the principle upon which my improved receiving circuit operates.

Although I have disclosed a receiving system which is used in connection with some form of detector, the auxiliary receiving circuits may be used with systems operating from undamped waves by the Hetrodyne method without departing from the spirit of the invention.

Although in the preceding description I have illustrated this receiving device as applied to the ordinary forms of receiving circuits for wireless telegraphy, it is to be understood that the application thereof is not limited to such use. It is to be understood that in general the receiving circuit

may be applied wherever pulsations or alternations of electric nature exist and wherever it is desired to render the receiving circuit sensitive to only certain previously predetermined tone frequencies.

I claim:—

1. Wireless telegraph apparatus, comprising a receiving circuit, and an auxiliary circuit, including a telephone, a variable capacity condenser and an inductance coil in 50 respect to which one terminal of each the receiving circuit and telephone is adjustable, for tuning the auxiliary circuit to a group-frequency.

2. Wireless telegraph apparatus, comprising a receiving circuit, and a plurality of auxiliary circuits for segregating electrical impulses of different group frequencies arriving in common at the receiving circuit, each provided with an inductance connected 60 at one terminal to the receiving circuit, telephones having one connection to said inductances, and another connection movable in respect to the inductances; and variable capacity condensers bridged across the inductance terminals.

3. The combination in a wireless telegraph apparatus, of a circuit for receiving electrical impulses of like radio-frequencies but different group-frequencies, means for 70 segregating all impulses of like group frequencies, including inductance coils and variable capacity condensers bridged across parts of the receiving circuit, and means combined with said segregating means, for 75 rendering said segregated group-frequencies intelligible, including telephones, each with a terminal adjustable along the companion inductance coil.

FREDERICK E. PERNOT.
